[57] CLAIM

The ornamental design for a hot beverage dispenser, as shown and described.

DESCRIPTION

FIG. 1 is a perspective view of a first embodiment of a hot beverage dispenser showing my new design;

FIG. 2 is a top plan view thereof;

FIG. 3 is a front elevation view thereof;

FIG. 4 is rear elevation view thereof;

FIG. 5 is a right side view thereof;

FIG. 6 is a bottom plan view thereof;

FIG. 7 is a front elevation view of an alternative embodiment thereof.

The left side view of the first embodiment, not shown, is a mirror image of the right side view shown in FIG. 5.

The rear, top, bottom and side views of the alternative embodiment are the same as for the first embodiment.
